[57] CLAIM

The ornamental design for an illuminated sign, as shown and described.

DESCRIPTION

FIG. 1 is a perspective view of an illuminated sign showing my new design;

FIG. 2 is a right side elevational view thereof;

FIG. 3 is a rear elevational view thereof; and

FIG. 4 is a sectional view taken along line 4—4 of FIG. 3.

The broken lines showing the numbers are for illustrative purposes only and form no part of the claimed design.

FIG. 3.

FIG. 4.
